(57) **CLAIM**

We claim the ornamental design for a digital audio disc player with tuner, as shown and described.

DESCRIPTION

FIG. 1 is a perspective view of a digital audio disc player with tuner, showing our new, original and ornamental design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a perspective view thereof showing the front panel being in the open position; and,

FIG. 9 is a front view thereof showing the digital audio disc player with tuner powered up.

The broken line showing on the drawing disclosure is for the illustrative purposes only and forms no part of the claimed design.
